UNITED STATES PATENT OFFICE.

RICHARD MATCHETT, OF MELBOURNE, VICTORIA.

FLUID-PRESSURE REGULATOR.

SPECIFICATION forming part of Letters Patent No. 601,878, dated April 5, 1898.

Application filed February 27, 1897. Serial No. 625,373. (No model.)

To all whom it may concern:

Be it known that I, RICHARD MATCHETT, a subject of the Queen of Great Britain, and a resident of No. 454 Collins street, Melbourne, 5 in the Colony of Victoria, have invented certain new and useful Improved Apparatus for Reducing the Pressure of Liquids and Gases, of which the following is a specification.

This invention has been devised to provide 10 improved means or apparatus by which liquids or gases under pressure may during their reticulation be automatically reduced to the proportion required.

Although my invention may be applied to 15 other liquids or gases, I shall for simplicity of explanation describe it with reference to reducing the pressure of carbonic-acid gas when it is desired to apply this gas to beer or wine previous to their being supplied to customers.

In order that my invention may be the more easily understood, reference may be made to the accompanying drawings, in which—

Figure 1 is a sectional elevation, while Fig. 25 2 is a plan, of my apparatus with some portions removed for the sake of clearness.

In the drawings, A, Fig. 2, represents a cylindrical shell or casing of metal, preferably brass, having attached thereto an inlet-tube 30 B and its connections, an outlet-tube C, a pressure-gage D and its parts, and a safety-valve E and its parts.

F, Figs. 1 and 2, is a metal cover arranged to screw by a peripheral thread at F' into the 35 enlarged portion of casing A. A portion of F at F² is squared or faced to permit a spanner to grasp it for the purpose of screwing F home. Into the top of F a screw-thread F³ is set for the purpose of receiving a screw-plug 40 G. This latter plug G terminates in a small shank G', around and below which a spiral spring H is set and so arranged as to exert a downward pressure upon a gripper-plate or diaphragm I. Under this gripper-plate or 45 diaphragm I is a circular plate K, preferably constructed of red rubber. This circular plate completely divides and separates the upper from the lower portion of the casing A and is of the full inner diameter of the enlarged part of the said casing A. K is kept 50 in position by a metal ring K', the latter being jammed by the screw-pressure of the cap

F at F'. On the under side of this circular plate K is another gripper-plate L, which exerts a vertical thrust, so as to grip the rubber plate between itself and the gripper I. The upward pressure of L is brought about by the spring M beneath pressing vertically against it. It will be noticed that the shank L' of L is screwed and has mounted upon it 55 one arm of a lever N and a lock-nut L². The spring M terminates at the bottom on a screw-plug O, which screws into the casing at A'.

Reverting to the lever N (see Fig. 1) it will be noticed that it is centered at N' in an upright N², said upright being either screwed in or otherwise fastened to the casing at A². The outer end of the lever N terminates in a pad or valve P and is so arranged that it will rise and fall with the movement of 70 the lever upon the valve-seat R. This latter is preferably constructed in the form illustrated; but I would have it understood that I do not confine myself arbitrarily to the exact arrangement of the valve and its seating. 75 R is attached to or set in the inlet-tube B, which is secured to the casing at A³.

T is a screwed union to which the high-pressure supply is attached, a washer T', of rubber or similar material, being employed to 80 assist in forming an air-tight joint.

C, Fig. 2, is an outlet-tube leading from the chamber beneath the division K and from which is led away the low-pressure gas.

D, Fig. 2, is a pressure-gage having a passage D', also communicating with the chamber below the division-plate K, its position being also shown on Fig. 1 by dotted circles D'.

E, Fig. 1, is an inverted spring safety-valve having a communication E' with the interior 85 of the casing A, and the pressure upon its escape-valve E² being regulated by the spring E², the strain of which is adjusted by the screw E³, which latter is provided with a milled head E⁴. It will thus be seen that an undue 90 pressure in the casing A will be relieved by said valve, and consequently will not be communicated to the vessel containing the wine or beer under treatment.

The *modus operandi* of my invention is as 100 follows: Presume that carbonic-acid gas at a pressure of one hundred pounds per square inch is to enter at T and that it is desired to be drawn off at the outlet C at five pounds

per square inch. The gas enters and passes along through T, B, and R and escapes into and fills the chamber beneath K and makes its exit by C, whence it is led to the wine or 5 or beer requiring treatment. When the wine or beer in the cask has become sufficiently charged or will not absorb the gas quickly enough, the pressure in the chamber under K will begin to rise until it reaches the prede- 10 termined point for which the pressure of the springs H and M has been adjusted—that is to say, about five pounds per square inch, as will be seen on the gage D. The slightest further increase of pressure will cause the 15 circular rubber plate K to rise or expand vertically and carry with it the gripper L, and synchronously its shank L' and lever N, so that the latter will close the valve P upon the valve-seat R, and thus prevent any further 20 ingress of the gas at such valve-seat until such time as the pressure gets below the point required, when the high-pressure gas will again enter to make up for any deficiency in the low-pressure supply. The state of the 25 pressure in the chamber under K can be seen by a glance at the gage D.

In adjusting my apparatus to deliver the gas or liquid at the required reduced pressure, as will be shown upon the gage D, the 30 screw-plugs G and O are carefully operated, so that spring M, on the one hand, may have sufficient compression to quickly push the lever N upward, (when the downward tension of the spring H has been overcome by the 35 pressure under diaphragm K,) and, on the other hand, that a sufficient compression is given to the spring H so that the gripper I will not permit the diaphragm K to rise until the required pressure under it has been ar- 40 rived at. It will thus be seen that the springs H and M preserve the equilibrium of the dia- phragm, and through this means automatic- ally control the action of the valve P.

I do not confine myself to the employment 45 of any particular material for the construc- tion of my apparatus; but in practice I have

found gun-metal to be suitable. I would also point out that where certain injurious or cor- rosive gases or liquids under pressure require to be reduced by my apparatus the parts 50 might be formed of special material—such as vulcanite, for instance.

Having now particularly described and as- certained the nature of my said invention and in what manner the same is to be per- 55 formed, I declare that what I claim is—

A fluid-pressure regulator, comprising the separable casings A F, provided with inlet and outlet pipes T and C, the diaphragm K interposed between said separable casings 60 and forming an upper and lower chamber, a gripper comprising two independent blocks arranged on opposite sides of the diaphragm, the upper block being provided with a stud and the lower block with a screw, the adjust- 65 able threaded plug G having a reduced ex- tension G', a coiled spring H, the end coils of which engage the extension and a stud of the screw and gripper sections respectively, and is confined between the two, a post N² having 70 a screw-threaded engagement with the sec- tion A of the casing, a bell-crank lever jour- naled to said post and having at one end a valve to control the inlet-passage, and hav- 75 ing at its other end a screw-threaded aper- ture through which projects the screw of the lower gripper-section, and by means of which the bell-crank may be adjusted to regulate its valve, a screw-threaded plug O secured to the lower section of the casing, a spring M 80 surrounding the lower end of the screw and engaging the plug O, the adjusting-nut L² on said screw above the end of the bell-crank lever, and the spring-actuated safety-valve E having the adjusting-plug E³, substantially 85 as set forth.

Signed at Melbourne this 15th day of Jan- uary, 1897.

RICHARD MATCHETT.
